(57) **CLAIM**

The ornamental design for an armchair, as shown and described.

DESCRIPTION

FIG. 1 is a front view of the armchair;

FIG. 2 is a left side view of the armchair shown reclined and with a footrest extended, the right side being a mirror image thereof;

FIG. 3 is a left side view of the armchair shown reclined and with the footrest retracted, the right side being a mirror image thereof;

FIG. 4 is a left side view of the armchair shown upright, not reclined, the right side being a mirror image thereof;

FIG. 5 is a perspective view from the rear of the armchair; and,

FIG. 6 is a bottom view of the armchair.
